UNITED STATES PATENT OFFICE.

THEOPHILUS VAN KANNEL, OF YARDVILLE, NEW JERSEY.

ARTIFICIAL-LIMB SOCKET.

1,305,573.

Specification of Letters Patent. Patented June 3, 1919.

Application filed March 19, 1918. Serial No. 223,300.

To all whom it may concern:

Be it known that I, THEOPHILUS VAN KANNEL, a citizen of the United States, residing at Yardville, county of Mercer, and 5 State of New Jersey, have invented certain new and useful Improvements in Artificial-Limb Sockets, fully described and represented in the following specification and the accompanying drawings, forming 10 a part of the same.

This invention relates to an improved means of connecting an artificial limb with the stump of a leg or arm, and the invention will be described herein in its application 15 to an artificial leg, although it will be understood that the construction and operation are practically the same when used in connection with an artificial arm.

When the limb has been amputated below 20 the knee or elbow, a leather socket is usually arranged to embrace the limb above the joint, which would be the thigh or upper arm. This part will be termed the "upper socket" herein.

25 In such cases, the artificial limb is provided at its upper end with a non-flexible socket adapted to embrace the lower end of the stump, that is, the portion below the joint.

30 Such lower socket is generally made of wood or fiber and does not require to be opened laterally; but the upper socket requires to be of flexible material, as leather, and capable of opening upon one side (preferably at the front, where it is most accessible), for application to the limb.

While my invention is particularly applicable to the upper socket, it can also be used where the lower socket is made with a 40 portion, or all, of flexible material, having a vertical opening, the edges of which are to be fastened together.

These two sockets are held in their proper relation by metallic joint-pieces and by a 45 flexible tie, the upper members of which extend upwardly nearly the entire length of the leather socket, to which they are permanently fastened, one on each side of the socket, by rivets or other means, while the 50 lower members are extended downward and

are permanently attached to corresponding sides of the wooden socket. The joints of these joint-pieces have their center of motion in line with that of the natural knee.

It should be observed that the knee is 55 larger than the portion of the limb just above the knee to which the flexible upper socket would be applied; and for this reason it is necessary to make the upper socket to open so that the thigh may be inserted in the socket. 60

My improvements relate to means for drawing the edges of the opening together and securing them in the closed position, in combination with means for adjusting the 65 diametrical size of this socket, in order to obtain at all times the required resistance to the thigh and preserve a uniform tension throughout the length of the socket.

The invention also includes improved 70 means for maintaining the joint-pieces in their original relation to one another when varying the diameter of the socket, and a means of limiting the degree of flexure of the joint-pieces. It also includes various 75 details of construction which will be hereafter described and claimed.

By the present invention there are no parts which require to be readjusted from day to day in applying the socket to the 80 thigh, but the means for adjusting the diameter and tension of the socket are wholly different from the means for securing the socket upon the limb, as will be understood from the following description.

85 In the annexed drawing, the socket-body is provided with hook-plates at opposite sides of its opening, and a hook-slide to engage the edges of the hook-plates, but any means of connecting the edges of the opening non-adjustably may be employed.

90 The application of the upper socket to the limb and the wearing of the artificial member, constantly causes the thigh to shrink where the upper socket is applied, 95 and the socket therefore requires to be comparatively larger when first applied and afterward to be reduced in diameter in accordance with the degree of shrinkage in the limb, and thus maintain the 100

same tension or pressure upon the limb to hold the artificial member firmly and to support its proportion of the weight of the wearer.

- 5 This shrinkage of the limb is often very great, and if the socket be contracted merely at the opening side to compensate for such shrinkage, it obviously draws both the joint-pieces forward of the diametrical line of the 10 socket, or from their original coincidence with the joint of the limb. Such displacement of the joint-pieces causes a great deal of friction and wear on the joints, as well as excessive strain, and often causes them to 15 break.

My invention provides means for contracting or expanding the diameter of the socket without displacing the joint-pieces, from coincidence with the joint of the limb.

- 20 This is effected by the means hereinafter pointed out, which will be understood by reference to the annexed drawing, in which Figure 1 is a front view of an upper socket for an artificial leg; Fig. 2 is a cross section of 25 the same on line 2—2 in Fig. 1; Fig. 3 shows the inner side of the hook-slide, and Fig. 4 the outer side of the same. Fig. 5 is an enlarged view in elevation; and Fig. 6 a 30 cross section of the parts to which the two adjusting lacers are applied.

Fig. 7 is an enlarged section of a socket with a lining of variable thickness; and Fig. 8 shows the means of connecting the upper and lower sockets by a flexible multiple connection.

- 35 A designates the body of the socket with its opening B in the front, at the opposite edges of which hook-plates *a* are riveted, and their adjacent edges are bent to form 40 longitudinal hooks *b* so as to readily engage inwardly turned hook-flanges *c* upon the opposite edges of a hook-slide *d*, to fasten the socket upon the limb. The engagement of the hooks *c* and hooks *b* is clearly shown 45 in Figs. 2 and 4.

The opening at the front of the socket is shown in Fig. 1 without the hook-slide, to clearly exhibit the bent edges of the hook-plates. When the socket is clasped upon the 50 limb the hook-slide is applied to the hooks *b*, as shown by the dotted lines *d*, at the upper end of the hook-plates *b* in Fig. 1.

- 55 The hooks *b* taper from their middle at *b*² toward their ends and are thus a little wider at the middle of their length than at either end, so that the flanges of the hook-slide are easily applied at their upper ends, but gradually press the inclined edges of the hooks toward one another as the slide is moved 60 downward into the position shown in Fig. 4.

When in this position, the bent flanges of the slide contact with the hooks *b* at the middle of their length, clearing both ends of the hooks *b* and *c* sufficiently to permit the 65 socket-parts at opposite sides of the division

to rock slightly in relation to one another, and thus equalize the pressure upon the thigh when bending the artificial limb, or when the pressure on the thigh is not equal at the top and bottom of the socket.

The precise form of the parts is not material, as it will be understood that the rocking bearing of the slide upon the hooks *b* may be effected by making these hooks without any taper, and tapering the hook-flanges *c* upon the hook-slide *d* inwardly toward the middle of its length, so as to locate the bearing-point of the hooks and flanges intermediate to the ends. The slide would operate the same if the hook-plates *a* were secured 80 upon the outer sides of the body *A* and the hooks turned toward the socket instead of outwardly.

In that case, the body of the slide *d* would slip inside of the hooks instead of outside, as 85 shown.

To facilitate the application of the slide to the upper ends of the hooks *b*, the top of one of the hooks (marked *b*¹ in Fig. 1) is cut away sufficiently to permit the slide to first engage the opposite hook *b* and afterward engage the hook at *b*¹. This avoids the necessity of holding the two hooks *b* carefully in the proper position to make the slide engage both at the same time. This arrangement 95 also enables the wearer to draw the left plate *b* over toward *b*¹, and overcomes the resistance of the thigh to the socket, and this operation can easily be performed without the use of light.

The space between the adjacent curved portions of the hooks *c* on the hook-slide *d* requires to be filled flush with the inner side of the socket, and for such purpose a strip of leather, or other hard pliable material *e*, is secured to the slide *d* to fill such space, as shown in Figs. 2 and 3.

Such filling strip is projected above the upper end of the slide to form a handle *e'* with which to manipulate the same, as 110 shown in Fig. 3.

Joint-pieces *f*, *f'* are shown attached (as by riveting) to opposite sides of the socket *A*, upon the ends of a diametrical or other pre-determined line, and in order to compensate for any change in the size of the limb, without changing the circumferential relation of the joint-pieces, I provide means to contract or expand the socket at both the front and the rear of the joint-pieces.

This means consists in forming two divisions of the socket one at the front and the other at the rear of a joint-piece, with adjacent means, as lacers, for closing the divisions.

Fig. 2 of the drawing shows a segment *A'* of the socket-body *A* with divisions at its opposite edges.

In this case, the joint-piece *f* is secured to the segment *A'* and such segment con- 130

nected to the body of the socket by loops with lacing-cords at the edges of the two divisions.

The lacings may be applied by sewing a folded strip g along each edge of the division by stitches g^2 , as shown in Figs. 2 and 5, with notches h cut out of the folds, leaving loops g' through which the cord h' is extended and tied in the usual manner.

10 Instead of forming the two divisions both at one side of the socket, as shown in Fig. 2, one of the divisions may be formed in the rear of one joint-piece and the other division at the front of the other joint-piece, 15 which will permit the contraction or expansion of the socket equally at the front and rear, and thus preserve their circumferential relation to one another upon a diametrical or predetermined line of the socket.

20 If the socket needs to be reduced, for example a half-inch in its periphery, the divisions at opposite sides of the joint-piece f would each be laced one-quarter of an inch tighter, thus effecting the reduction of one-half an inch and still hold the joint-piece f diametrically opposite to the joint-piece f' .

The socket thus constructed is obviously provided with separate means for closing the opening, and for varying the adjustment 30 of the size of the socket, and such independent operation of these two agencies constitutes a very important improvement in such constructions.

35 It will be noticed that the lacing cords are not unfastened and changed when the socket is removed from the limb in the usual course of use, and that their insertion through the loops g' positively prevents their accidental displacement.

40 The lacers which form the means of adjusting the socket to the limb cannot lose their adjustment when the socket is put on and off, because the opening of the socket is effected only by withdrawing the hook-slide d . This permits the lacers to maintain their adjustment as long as the socket 45 needs no change.

A flap i is shown attached at one edge to the interior of the socket and extended in 50 side over both of the lacers h' and the slide d , so as to secure a smooth even surface throughout within the socket, as usual.

55 A means to compensate for the shrinkage or expansion of the limb without deranging the proper relation of the joint-pieces f , f' , is shown in enlarged view in Fig. 7, in which the socket is divided only at the front and is closed by a hook-slide as already described.

60 In this form the compensation is provided by furnishing a variable filling for a double lining in the socket, which lining without material trouble can be made thicker or thinner at any time to compensate for the 65 shrinkage or expansion of the limb at such

time. This lining consists of two flaps l and l' which reach entirely around the interior of the socket and are secured to the inside of the socket at h near one edge of the opening B.

70 A suitable filling l^2 formed of fibrous material or layers of felt or textile goods, is placed between these flaps to make the socket snugly fit the limb when it is applied thereto, the lining being forced outward against 75 the inner wall of the socket when in use.

The two flaps hold the filling securely in any part of the socket where it is primarily adjusted, and the filling may thus be made of uniform thickness between the two flaps, 80 or may be made thicker near the top or bottom of the socket wherever the pressure requires it. The lining is entirely accessible, to separate the flaps and make the lining thicker or thinner as desired, to comfortably 85 fit the limb of the wearer.

It sometimes occurs that the upper socket gets out of alinement with the lower one, in which case proper compensation can be obtained by placing more or less filling on 90 one side or the other. If the tension is greater at the top than at the bottom of the socket, or the reverse, the wearer will suffer great discomfort, be unable to walk with ease, and the unequal pressure will interfere 95 with the circulation of the blood in the limb.

To attach the socket to the limb, the loose end of the lining is drawn out through the opening, when the thigh may be placed in the socket, the loose end replaced, and the 100 socket fastened by the hook-slide.

105 It will be noticed that this construction of lining compensates for variation in the size of the limb without in any way deranging the circumferential relation of the joint-pieces, and in this respect is an exact equivalent of the two divisions with lacers h' that are shown in Fig. 2.

In the artificial leg such as described, it is 110 usual to provide a dead stop in the joints of the two joint-pieces to prevent the natural knee from flexing beyond the normal stopping point; otherwise such flexing would be liable to cause a fracture of the natural knee, but the strain on the artificial joints is sometimes so great that these stops would give way under severe strain as in lifting or jumping.

115 To make this feature of the artificial leg more secure, it is usual to provide a strong 120 check-strap, one end being fastened to the upper socket and the other to the lower socket, and this check-strap must be provided with very exact adjustment. This connection is generally formed with a bulky 125 leather strap having a lacing cord running through metallic eyelets which are inserted in a leather hanger sewed on the outside of the lower rear edge of the leather socket.

130 This hanger in its normal strain pulls out-

ward that portion of the lower socket to which it is attached to a considerable distance and somewhat above the edge of the socket.

5 This produces a sharp cutting edge on the socket which forces itself into the flesh of the thigh, causing great pain and inconvenience to the wearer. This strap, being necessarily connected with the rear side of the 10 socket so that it lies under the knee of the wearer, also causes much discomfort and inconvenience when sitting down.

With my improvement, the use of such means is avoided, and a very flexible union 15 of the sockets is secured, with all the strength that is necessary to hold the two sockets in the proper relation, by means of a flexible multiple connection.

To do this, I sew by stitches m^2 a looped 20 piece of leather, which I call a tongue m , inside the lower edge of the leather socket shown in Figs. 1 and 8. I have this tongue m extend some distance up the socket, as shown in dotted lines m' , and permit the 25 folded edge to extend downward a short distance below the lower edge of the socket.

Notches are cut through this folded edge, producing pliable loop-eyelets o , as above mentioned. A similar tongue m' is fastened 30 to the lower socket C some distance below its upper edge, as shown in Fig. 8, the object being to obtain considerable distance between these two series of loop-eyelets. A suitable lacing cord p or ordinary tape is 35 run through all the loops and tied as usual. The effect of sewing the tongue inside the socket, instead of outside, is that this tongue will constantly pull the edge of the socket away from the natural member, thus giving 40 great ease and comfort to the wearer.

The constructive features claimed herein afford a great advantage in the application and use of the limb-socket, as they permit the instantaneous removal of the socket 45 from the limb and furnish means to maintain the joint-pieces in the proper relation to the joint of the limb, while accommodating the size of the socket to the limb.

The use of the independent non-adjustable means for securing the socket upon the 50 limb permits the division or gap where the socket is opened to be closed by a metallic fastener like the slide d , which furnishes the sole means of securing the edges of the opening together, and operates to lock the socket upon the limb by a single movement of such fastener, which may be applied without the need of light.

Having thus set forth the nature of the invention what is claimed herein is:

1. In an artificial limb-socket, the combination, with the socket-body having an opening at the front, of hook-plates secured to opposite sides of the opening and formed with hooks tapered upon their edges from the middle toward both ends, and a slide having flanges upon the edges adapted to engage the said hooks and to rock upon the projecting middle portion of the hooks when engaged therewith. 60

2. In an artificial limb-socket, the combination, with the socket-body having an opening at the front, of hook-plates secured to opposite sides of the opening and formed with hooks upon their edges, one of said hooks being cut away at the top to make it shorter than the opposite hook, and a slide having flanges upon the edges adapted to engage the said hooks. 65

3. In an artificial limb-socket, the combination, with the socket-body having an opening at the front with non-adjustable means for securing the edges of such opening together, joint-pieces secured at the sides of the body, a division in the body at the front 80 of a joint-piece and a division of the body at the rear of a joint-piece, the edges of the divisions being secured adjustably, whereby the diameter of the socket can be varied without varying the relation of the joint-pieces to the diametral line of the socket. 85

4. In an artificial limb-socket, the combination, with the socket-body having an opening at the front with non-adjustable means for securing the edges of such opening together, two divisions in one side of the body at opposite edges of a segment, one joint-piece being secured to the said segment, and the opposite edges of the segment being connected adjustably to the body of the socket, 90 whereby the diameter of the socket can be varied without varying the proper relation of the joint-pieces. 95

5. The combination, with an artificial limb-socket having an opening at the front 105 and means to secure the edges of the opening together, of two flaps attached at adjacent points to the interior of the socket and extended within the entire periphery of the socket and having a laminated pad between 110 the two flaps proportioned to fit the socket suitably to the limb of the wearer.

In testimony whereof I have hereunto set my hand.

THEOPHILUS VAN KANNEL.
